UNITED STATES PATENT OFFICE.

JOHN MILLAR, OF ARLINGTON, NEW JERSEY.

ROAD WHEEL.

Application filed July 9, 1921. Serial No. 433,406.

To all whom it may concern:

Be it known that I, JOHN MILLAR, a citizen of the United States, and a resident of Arlington, in the county of Hudson and State of New Jersey, have invented certain new and useful Improvements in Road Wheels, of which the following is a specification.

This invention relates to tires for automobiles, or the like; and has for its main object and feature the production of a simple, efficient and inexpensive punctureless tire.

In the accompanying drawings the invention is embodied in a concrete and preferred form in which—

Fig. 1 is a transverse vertical sectional view of a tire embodying the invention:

Fig. 2 is a side elevation partly broken away and in section:

Fig. 3 is a detail sectional view on the plane of line 3—3 of Fig. 1:

Fig. 4 is a detail sectional view of one of the intermediate thrust members.

1 indicates a cushion, preferably a pneumatic cushion, located remote from tread 2 and which may be adjacent to the hub of the wheel; or, as shown in the present instance, between cheeks 3 of a disc wheel. These cheeks are bolted together in any suitable manner as by bolts 4 and are provided with a filling member 5 of wood or other material that also acts as an abutment member for the cushion. The conformation of cheeks 3 is of such character as to afford an enlarged space 6 in which the pneumatic cushion is located. This pneumatic cushion may be, and in the present instance is, a tube with both ends closed as at 7 and in butting engagement and may be introduced into the space 6 through opening 8 conveniently provided with a removable cover 9. Valve 10 in the pneumatic cushion extends between the aforesaid cheeks 3 and up through an opening in member 5 and may be rendered accessible by means of an opening 11 in one of said cheeks provided with an adjustable cover 12.

13 indicates a plurality of radially movable inner segmental members, the number of which may vary but here consisting of four such members. 14 indicates a plurality of radially movable outer segmental members, there being in the present instance twelve such members. The inner and outer segmental members are connected by means

of intermediate thrust members that are made extensible as by being formed in two telescoping parts 16 and 17, each of which parts is provided with an enlarged head 18 and 19. As here shown, each inner segment 60 is provided with three sockets 20 partly cut away, as shown in Fig. 3, to admit of introduction of heads 18, said heads being somewhat elongated so as to pass under the flanges of the sockets aforesaid; and which, 65 after being introduced, may be turned around to bring the elongated parts of the heads under the flanges of the sockets. Outer segments 14 are also provided with sockets 21 formed by flanges in adjacent 70 ends of two adjoining sections 14; each section 14 extending from substantially the center of one head 19 to the center of the next adjacent head 19. Suitable means are provided for guiding the thrust members. 75 In the present instance these means take the following form: 22 indicate guides through which members 17 of the extensible thrust members pass, said guide members being provided with projections 23, that pass 80 through cheeks 3, the outer ends of which are threaded to receive nuts 24 to thereby hold the guide members stationary with respect to said cheeks, and to bolt said cheeks together at their outer edges. To properly 85 guide tread 2, annular guide members 25 are provided which are conveniently clamped between cheeks 3 and nuts 24. The inner ends of guides 22 are provided with cups 26 containing a washer 27 bearing 90 against sockets 20 of inner segmental member 13. To prevent ingress of dust, cheeks 3 are bent inwardly at their outermost edges 28 to form a shield. Tread 2 is continuous and the outer segmental members 14 may be 95 secured to it in any suitable manner as by being imbedded in said tread, as shown.

It will now be understood that during the revolution of the wheel that portion of the tread which is against the ground will cause that segment 14 which is adjacent thereto to cause a thrust member 16—17 to move inwardly through guide 22 and will transmit the thrust to inner segmental member 13. Because the intermediate thrust members 100 are extensible, the thrust produced by one of these members will cause segmental member 13 to pull only inner part 16 of the next adjacent thrust member with it, and said segmental member 13 will slide against the 105 110

inner walls of cheeks 3 and thus transmit the thrust to cushion 1. The tread in producing this action will slide in guides 25.

I claim—

- 5 A road wheel comprising: cheeks composing the body of the wheel, a cushion located between said cheeks and remote from the periphery of the wheel, an abutment member against which the cushion acts, a plurality of guides located between the cheeks, extensions on said guides passing through the cheeks and bolted thereto, annular guide members carried by the cheeks, a plurality of outer segmental members having sockets
- 10

on their inner faces, a tread carried by the outer segmental members between the annular guides, a plurality of inner segmental members, bearing against the cushion between the cheeks, having sockets, and a plurality of extensible thrust members passing through said guides and having heads in engagement with the sockets of the inner and outer segmental members.

Signed at Arlington, in the county of Hudson and State of New Jersey, this 1st 25 day of July 1921.

JOHN MILLAR.
